UNITED STATES PATENT OFFICE.

LAURITS OLUF LARSEN, OF PERTH AMBOY, NEW JERSEY.

LIFE-BOAT.

1,090,923.

Specification of Letters Patent. Patented Mar. 24, 1914.

Application filed January 17, 1913. Serial No. 742,674.

To all whom it may concern:

Be it known that I, LAURITS OLUF LARSEN, a citizen of Denmark, residing at Perth Amboy, in the county of Middlesex and State of New Jersey, have invented certain new and useful Improvements in Life-Boats, of which the following is a specification.

- This invention relates to improvements in collapsible life boats and its object is to produce a boat of this class that is readily assembled and locked in operative position and as readily collapsed; lightness, durability and cheapness of manufacture are other objects.
- 15 The boat comprises a plurality of longitudinal ribs terminally hinged to the keel and connected by a canvas covering and transverse ribs adapted to retain the longitudinal ribs in assembled position.
- 20 The invention consists in the combination and arrangement of parts to be herein-after fully described in the following specification, pointed out in the claims and illustrated in the accompanying drawings which 25 form a part of the specification and in which—

Figure 1 is a plan of my boat in assembled position. Fig. 2 is a side elevation of the boat collapsed. Fig. 3 is a longitudinal section taken on line 3—3 of Fig. 1. Fig. 4 is a transverse section taken on line 4—4 of Fig. 1. Fig. 5 is a section taken on line 4—4 of Fig. 1 after the boat has been collapsed. Fig. 6 is a detail of the end of a cross rib 35 in side elevation showing the fastening device employed. Fig. 7 is a plan of Fig. 6. Fig. 8 is a section taken on line 8—8 of Fig. 9. Fig. 9 is a detail plan of a portion of a longitudinal rib showing its connection with 40 the cross rib and the fastening means for the two.

Like reference characters indicate corresponding parts throughout the several views.

45 My boat comprises a keel 1 and to the extremities of the same the extremities of outer longitudinal ribs 2, 2 are hinged as at 3, 3. Intermediate longitudinal ribs 4, 4 shorter than the outer ribs are also hinged to the keel 1 between its extremities as at 5, 5. Secondary intermediate ribs 6, 6 shorter than the intermediate ribs 4, 4 are also terminally hinged to the keel 1 as at 7, 7 and inner longitudinal ribs 8, 8 are hinged to the keel 1 as 55 at 9, 9. The bases of the several longitudinal

ribs are covered with a continuous canvas covering 10 which when the ribs are extended and in operative position is drawn taut and when the ribs are in inoperative position, as shown in Fig. 5, hangs in folds as 60 shown.

When in assembled position the longitudinal ribs are kept in place through the medium of a plurality of transverse ribs 11. The ends of these ribs pass through the outer longitudinal ribs and are reduced as at 12 and apertured to receive the end 13 of an angular pin 14 provided with a knob 15 and held in operative position by a spring 16 secured to the longitudinal rib. The body 70 of the cross rib is notched to engage the several longitudinal ribs between the outer longitudinal ribs and the keel and to retain them in operative position. Angular friction fingers 20 pivoted to the intermediate, 75 secondary intermediate and inner longitudinal ribs engage the cross ribs to hold them in adjusted position.

17 is a seat normally resting as at 18 upon its support 19 which is hinged to the keel 80 and said seat is hinged at its ends to the intermediate longitudinal ribs and adapted to be collapsed when said ribs are collapsed.

Operation: In assembling my boat the longitudinal ribs are drawn away from the 85 keel laterally as far as the hinges will permit and the cross ribs then placed in position to hold said longitudinal ribs operative. A canvas top may be secured to the outer longitudinal ribs if desired.

80 What is claimed is:—

1. In a collapsible life boat comprising longitudinal ribs and cross ribs adapted to interlock therewith, friction fingers carried by said longitudinal ribs for releasable engagement with said cross ribs, pins carried by said longitudinal ribs for releasable engagement with the terminations of said cross ribs and yieldable locking means carried by said longitudinal ribs for engagement with 95 said pins to retain them in operative position.

2. In a collapsible life boat comprising longitudinal ribs and cross ribs adapted to interlock therewith, friction fingers carried by said longitudinal ribs for releasable engagement with said cross ribs, pins carried by said longitudinal ribs for releasable engagement with the terminations of said cross ribs, flexible locking means carried by 100 105 110

said longitudinal ribs for engagement with said pins to normally retain them in operative position and handles for said pins whereby the said flexible locking means may be thrown out of operative position to permit the collapse of the boat.

In testimony that I claim the foregoing

as my own I have hereto affixed my signature in the presence of two subscribing witnesses.

LAURITS OLUF LARSEN.

Witnesses:

S. M. LIPSCOMB,

MARGARET HARNED.
